UNITED STATES PATENT OFFICE.

WILLIAM BECKMAN, OF SEALY, TEXAS.

OIL-BURNER.

1,350,917.

Specification of Letters Patent.

Patented Aug. 24, 1920.

Application filed January 29, 1920. Serial No. 354,861.

To all whom it may concern:

Be it known that I, WILLIAM BECKMAN, a citizen of the United States, residing at Sealy, in the county of Austin and State of Texas, have invented certain new and useful Improvements in Oil-Burners, of which the following is a specification.

This invention relates to oil burning stoves.

10 An object of the invention is to provide a stove having an air inlet within the heating chamber for warming the air before it enters the combustion chamber.

15 A further object of the invention is to provide a gas generating drum centrally located within the stove in which the oil is fed into the drum from the top when it drops on a conical heated plate where it is vaporized and the vapor collected within 20 the drum where it is preheated before being mixed with air for burning in an inverted burner.

25 Another object of the invention is to provide a stove having an external heating chamber around the air inlet and a gas generating drum and chamber within the air chamber, the oil feed pipe entering from the top so that the oil will be converted into 30 gas and the gas and air thoroughly heated before being mixed for burning.

Still another object of the invention is to provide a stove with an air inlet and a gas generating chamber, wherein the gas from a narrow annular opening at the bottom 35 of the gas generating chamber and heated air are drawn through narrow adjacent concentric openings by the draft in the heating chamber which is concentric to the air and gas generating chambers, so that the 40 gas will be drawn outwardly from said annular opening in the gas chamber and will be mixed and burned with the air as it passes under the annular adjacent air opening, the flame and heat passing outwardly concentrically into the heating chamber.

45 The invention also comprehends other improvements in the particular construction and arrangement of parts which will be more particularly pointed out in the specification and claims.

In the drawings:

Figure 1 is a vertical sectional view through the stove.

50 Fig. 2 is a transverse section on line 2—2 of Fig. 1.

Fig. 3 is a partly disassembled view.

1 indicates a casing or stove body which forms a heating chamber 2, the casing being provided with an opening 3 for the flue pipe 4, and being supported on legs 5.

60 A cylindrical member 6 is mounted in the casing 1, at the top thereof, and forms an air heating chamber 7. A tubular member 8, is mounted within the cylindrical member, and spaced therefrom, on an inclined deflector 9, attached to the cylindrical member, and extending from the tubular members beyond said cylindrical member into the heating chamber. The tubular member has the upper end closed by a cover 10 and is 70 provided near the bottom with a series of openings 11.

75 A drum 12 is removably and adjustably mounted within the tubular member, having the upper end closed, and the lower end open and terminating near the lower open end of the tubular member to form an annular air passage into a combustion chamber 13.

80 The drum is provided with an external flange 12' near the lower end contacting with the tubular member to form a dead air space between the drum and the tubular member above the flange. An oil supply pipe 14 is connected to the top of

85 the drum, communicates therewith and extends upward through the air chamber and has a funnel 14^a secured to the top thereof.

90 A rod 15 adjustably mounted in the drum has a conical plate 16 secured thereto so that the bottom edge is adjacent the bottom edge of the drum but capable of adjustment with respect thereto. The conical plate forms an annular gas passage with the drum to the combustion chamber 13, adjacent the annular air passage.

95 A drip pan 17 is adjustably secured on rod 15 below the conical plate 16 and forms a container for holding a starting charge. The drum 12, drip pan 17 and attached parts are removable from the stove as is shown in Fig. 100

3 for cleaning purposes.

A cover or damper 18 is adjustably mounted to open or close the air chamber 7 as indicated at 19.

105 A partition 23 is placed in the bottom of the stove and a false bottom 24 is carried thereon, the combustion chamber 13 being formed between the false bottom and the inclined deflector 9. The space below the false bottom is filled with sand as indicated 110

at 25. When the parts are in place the drip pan 17 rests on the false bottom.

The body of the stove is provided with a door 26 for access to the combustion chamber so the starting charge may be ignited or the flame observed.

To use this stove, a starting charge, for instance, gasolene is poured into the funnel at the top and the fuel runs down into the pan 17, and is ignited through the door 26.

The air for the combustion of the gasolene comes in at the top of the stove and through the air chamber 7 down around the tubular member 8, passes through the openings 11 and the annular air passage when it mixes with the gasolene vapor to form a combustible charge. The flame passes outwardly around the deflector and the exhaust gases pass up through the heating chamber and out the flue pipe 4.

The heat of the starting charge warms the conical plate 16 and the cylindrical member 6, so that the air in the air chamber 7 is warmed, and oil fed into the funnel 19 at the top of pipe 14 is warmed and is evenly distributed over the conical plate 16 on which it is vaporized, filling the drum 12 with vaporized gas, which becomes further heated and passes out the annular gas passage to the combustion chamber. The draft in the flue draws this gas outwardly from the gas passage uniting with the air coming through the air passage and beginning to burn. The flame passes out around the deflector and up into the heating chamber.

After the starting charge has burnt out, the gas from the drum continues to burn beginning adjacent the lower edge of the wall of drum 12.

The supply of fuel may be regulated from some external source and the air supply is regulated by adjusting the damper 18 at the top of the air chamber. This regulation of air and oil permits adjustment to obtain a perfectly combustible mixture. To further obtain adjustment for the latter purpose the conical plate 16, and the drum 12 are adjustably constructed, so that relative adjustment may be had between the plate 16 and the drum; and the drum and tubular member.

In the construction as shown it will be obvious that the air chamber and gas generating drum are positioned in the center of the heating chamber, so that the incoming air and the gas in the drum will be pre-heated before passing out of the annular openings at the bottom to encourage a complete combustion of the gas.

It will also be noted that the dead air space formed above the drum prevents the cool air in the top of chamber 7 from cooling the gas in the drum.

What I claim is:

65 1. In an oil burner the combination of

a casing, a flue pipe connected therewith, a cylindrical member supported in and spaced from the walls of the casing to provide a heating chamber, an adjustable damper on the top of said cylindrical member, a tubular member within the cylindrical member and spaced therefrom, to form an air heating chamber and formed near its bottom with a series of openings, a flame deflecting plate extending from the bottom of the tubular member into the heating chamber, an inclined bottom spaced from the deflecting plate to form a combustion chamber and flame passage, a drum closed at the top and disposed within and spaced from the tubular member, a conical plate within the drum having the periphery adjacent the bottom edge of the drum, a drip pan below the conical plate and an oil supply pipe extending from and connecting with the drum. 85

2. In an oil burner, the combination of a cylindrical member, a damper for regulating the admission of air to the cylindrical member, a tubular member within and spaced from the cylindrical member and closed at the top and open at the bottom, an inclined deflecting plate extending from the latter to the former, the tubular member having air inlet openings adjacent the bottom, a drum within the tubular member, closed at its top and open at its bottom and spaced from the tubular member, an inverted conical plate within and near the bottom of the drum to deliver vapor adjacent the air inlet ports, and a pipe for supplying oil to the conical plate. 95

3. In an oil burner the combination of a casing, a cylindrical member within the casing, a damper for regulating the admission of air to the cylindrical member, a tubular member closed at the upper end and formed with a series of openings near the lower end, an inclined deflector extending from the tubular member beyond the cylindrical member, a drum closed at the upper end adjustably mounted within the tubular member and having the walls spaced therefrom, a pipe for supplying oil to the drum, a conical plate adjustably mounted in the drum, a drip pan mounted below the plate, and an inclined bottom spaced from the inclined deflector to form a combustion chamber and flame passage, whereby the conical plate, drum, and tubular member, have the bottom edges adjacent to form an inverted burner, vaporized oil entering the combustion chamber through the annular opening formed between the conical plate and the drum and air entering the combustion chamber through the annular opening between the drum and the tubular member. 120

4. In an oil burner the combination of a casing, a cylindrical member within the casing, a damper for regulating the admission of air to the cylindrical member, a tu- 130

bular member within the cylindrical member, closed at the top and having the walls spaced from the cylindrical member, and formed with a series of openings near the bottom edge, an inclined deflector extending from the tubular member beyond the cylindrical member, a drum closed at the top mounted within the tubular member, having the walls spaced therefrom and having a flange thereon near the bottom edge extending outwardly and contacting with the tubular member to form a dead air space above the flange between the drum and tubular member, a conical plate mounted in the bottom portion of the drum, the periphery of the conical plate, bottom of the drum and bottom of the tubular member terminating adjacent one another, a drip pan below the conical plate and an oil supply pipe communicating with the drum, whereby an annular inverted burner is formed at the bottom of the drum by the conical plate, drum and tubular member.

5. In an oil burner, the combination of a deflecting plate, a drum surrounding the deflecting plate having the edge spaced therefrom, a member forming a dead air space around the drum provided with holes at the bottom thereof, the edge terminating adjacent the edge of the drum and an air chamber surrounding the member.

6. In an oil burner, the combination of a deflecting plate, a drum surrounding the deflecting plate, having the edge terminating adjacent the edge of the deflecting plate, a tubular member surrounding the drum, spaced therefrom and having its edge terminating adjacent the edge of the drum, an air chamber surrounding the tubular member, a passage for air in the bottom edge of the tubular member, and means for admitting fuel to the drum.

7. In an oil burner, the combination of a deflecting plate, a drum having the bottom edge terminating adjacent and spaced from the edge of the deflecting plate, a tubular member surrounding the drum and spaced

therefrom, and provided with air passages, an air chamber surrounding the tubular member, and a flame deflector extending from the tubular member and forming the bottom of the air chamber.

8. An oil burner comprising a deflecting plate, a drum, the edge of which terminates adjacent the edge of the deflecting plate and spaced therefrom to form a gas passage, a tubular member surrounding the drum and spaced therefrom to provide a dead air space around the drum and also formed with an air passage at the bottom adjacent the gas passage, an air chamber surrounding the tubular member and communicating with said air passage, whereby gas passing through the gas passage is mixed with air from the air passage for combustion which begins adjacent the passages.

9. An oil burner comprising a deflecting plate, a drum forming a gas generating chamber therewith having an annular gas passage at the bottom, a dead air space surrounding the drum, an air chamber surrounding the dead air space and communicating with an annular air passage adjacent the gas passage and concentric therewith, and means for admitting fuel to the drum, whereby the gas and air mix as they leave the annular passages and burn adjacent thereto.

10. An oil burner comprising a deflecting plate, a drum forming a gas generating chamber therewith having gas passage at the bottom, a tubular member surrounding the drum spaced therefrom, and forming an air passage therewith adjacent the gas passage, a cylindrical member surrounding the tubular member and spaced therefrom to form an air chamber and communicating with the air passage and a flame deflector extending from the tubular member to the cylindrical member.

In testimony whereof I affix my signature.

WILLIAM BECKMAN.
